UNITED STATES PATENT OFFICE

151,349

DESIGN FOR A TRAILER

William Josephian, Oakland, Calif.

Application July 19, 1947, Serial No. 140,392

Term of patent 14 years

(Cl. D14—3)

To all whom it may concern:

Be it known that I, William Josephian, a citizen of the United States of America, residing at 2205 Magnolia Street, Oakland, in the county of Alameda and State of California, have invented a new, original, and ornamental Design for a Trailer, of which the following is a specification, reference being had to the accompanying drawing, forming part thereof.

Fig. 1 is a perspective view of a trailer, showing my new design.

Fig. 2 is a top plan view of the trailer.

Fig. 3 is a side elevation of the trailer.

Fig. 4 is a rear elevation of the trailer.

I claim:

The ornamental design for a trailer, as shown.
WILLIAM JOSEPHIAN.
